UNITED STATES PATENT OFFICE.

CHARLES H. PERKINS, OF PROVIDENCE, RHODE ISLAND.

METHOD OF TREATING STOCK FOR HORSESHOE-CALKS.

SPECIFICATION forming part of Letters Patent No. 312,505, dated February 17, 1885.

Application filed July 25, 1884. (No model.)

To all whom it may concern:

Be it known that I, CHARLES H. PERKINS, of the city and county of Providence, and State of Rhode Island, have invented a new and Improved Method of Treating Stock for Horseshoe-Calks, of which the following is a full, clear, and exact description, reference being had to the accompanying drawing, forming a part of this specification.

10 My invention relates to that class of stock for horseshoe-calks which consists of a bar of iron or steel provided at intervals with tips, which are designed to be driven into the heated shoe for the purpose of strongly uniting the calk to the shoe.

15 The object of my present invention is to harden and lengthen and point the tips so that they shall more effectively perform their required function.

20 To this purpose my invention consists in cold-rolling or swaging the stock, whereby the tips are hardened, lengthened, and pointed, as hereinafter described.

25 In the accompanying drawing, the figure illustrates in perspective a stock-bar embodying my invention, the results of my improved treatment being indicated in dotted lines.

30 In the said drawing, A designates the bar, which, when cut into proper lengths, forms the calks. B B designate the tips, and c c indicate the points at which the bar is to be cut.

35 The bar, previous to its treatment in accordance with my present invention, is rolled of unequal thickness, the edge provided with the tips being wider than the opposite edge, so that the wider edge will be next to the shoe when the calk is secured thereto. The bar is first rolled between rolls which form a continuous rib upon the wider side of the bar, and then between rolls which are provided at

intervals with cavities shaped to conform to the shape of the tips, so that the tongue is rolled down at all points excepting where the tips are formed. The tips may be formed by 45 swaging or otherwise, instead of rolling, as described, and the calks are designed to be furnished to the trade in the form of bars, each calk being struck off from the bar by the shoer as required.

50 The above description is merely preliminary to a complete comprehension of the method constituting my present invention. After the tips B—one or more of which may be formed for each calk—have been rolled, the bar is cooled, 55 and is then passed in a cold state through rolls which are so shaped peripherally as to lengthen and point the tips, as is shown at b in the drawing. During the lengthening and pointing of the tips they are also hardened, so that 60 they will not bend or soften while being driven into the heated shoe.

Instead of cold-rolling the stock as above described, the same results may be produced by swaging the stock in a cold state by suitably-shaped dies. This result is important, 65 because it insures the proper position of the calk upon the shoe, the tips B when not hardened being liable to bend and soften, thus rendering the proper attachment of the calk 70 difficult.

Having thus described my invention, I claim as new and desire to secure by Letters Patent—

75 The method herein described of treating horseshoe-calk stock, consisting in cold-rolling or swaging the bars having the tips for the purpose of hardening, lengthening, and pointing the tips, as described.

CHARLES H. PERKINS.
